PATTERN COPYING MACHINE

George Francis Ryan, Lynn, Mass., assignor to
 United Shoe Machinery Corporation, Paterson,
 N. J., a corporation of New Jersey

Application January 28, 1931, Serial No. 511,826

50 Claims. (Cl. 33—23)

This invention relates to pattern copying machines in which a model is copied, generally in magnified or reduced dimensions, in a work piece. It is disclosed as embodied in a so-called pattern 5 grading machine, for making shoe upper patterns from model patterns of the "model size" (which, in women's work, is ordinarily 4B). The illustrated machine is of the type shown in United States Letters Patent No. 1,807,195, granted May 10, 1931, on the application of E. H. Burke, and in my prior application Serial No. 432,866, filed March 3, 1930. While the invention has been described in relation to a pattern grading machine it is not necessarily limited to machines of this 15 type, or even to two-dimensional as distinguished from three-dimensional machines.

A pattern grading machine of the type disclosed contains two pantographs which geometrically magnify the length and width of the model 20 independently. That is, all lines drawn in the model pattern parallel to its length are multiplied in length by a constant, and all lines drawn in it parallel to its width are multiplied in length by an independent constant, and reproduced in 25 the work. A shoe upper part cut from a pattern so graded from a model pattern will fit a last graded in the ordinary manner in a last lathe. Such lasts are, however, unsatisfactory, particularly in the manufacture of women's shoes, because of the intolerable variations in toe spring 30 introduced by the width grader and they have to be "bent" back to a satisfactory shape by sawing opposite slots and wedging one until the other closes, or by cutting a corrected last directly in a special lathe, such, for example, as is shown in 35 United States Letters Patent No. 1,362,183, issued December 14, 1920, on the application of L. B. Whipple, or in United States Letters Patent No. 1,362,185, issued December 14, 1920, on the application 40 of S. E. Boynton. Such corrected lasts cannot be fitted by uppers graded in the ordinary way, and it has been necessary to improve the pattern grading machine so that it will in effect bend the model or, in another way of looking at 45 the matter, reproduce from the model a bent work piece. This problem has been treated in United States Letters Patent No. 1,520,075, issued December 23, 1924, on the application of R. M. Packard, reissued as Patent No. 18,032, April 7, 50 1931, and in the Burke patent above mentioned.

Pattern copying machines of either of the two types mentioned, that is, for reproducing solid or flat models, comprise four primary instrumentalities, model holder, work holder, model foil 55 lower and tool, interconnected by pantographic

mechanism, whereby the movement of the follower around the pattern controls the movement of the tool around the work. These movements are to be considered as relative movements, because it is unnecessary that all of the instrumentalities actually move. In the last lathe they all move; in the pattern grading machine the model and work are normally motionless.

For the purpose of dealing with the problem described above, all four of the machines of the 10 patents and application mentioned embody the same fundamental principle. In each a movement of one of the primary instrumentalities, in addition to that characteristic of the normal reproductive action of the machine, is effected 15 continuously in a certain direction during a part of the reproduction, by virtue of a movement of another of the primary instrumentalities in a direction transverse to the first-named direction. If the model and work are regarded as divided 20 into corresponding series of thin laminae or strips (herein called "differential elements") all parallel to the direction of this additional movement, the corresponding elements in the work will then appear in positions shifted relatively to those of 25 their prototypes in the model; that is, each will be slid a little along its neighbor. Thus the side profile of a last or pattern produced from a given model can be varied by such a shifting of differential elements in a vertical direction.

In the machine illustrated in Patent No. 1,520,075 the model is moved parallel to its length and width independently, by means of cams. The machine shown in the Burke patent above mentioned is considerably simpler, but has dealt 35 with entire success with the practical problems arising in the pattern grading shop, where the broader capability of the former machine is unnecessary. In both these machines the desired distortion of the normal pantographic reproduction can be effected at any selected portions of the work.

The invention of my application Serial No. 432,866, filed March 3, 1930, improved still further the two machines just mentioned. That improvement will be better understood from a brief consideration of one specific problem, the solution of which it simplifies. Suppose that it is desired to cut a 5B half pattern (that is, a pattern which will cover one side of a last) from a 4B model half pattern, and that the toe spring difficulty is to be corrected by dropping the shank portion gradually from the ball to the heel breast portions, by shifting one of the four primary instrumentalities widthwise while this portion of the 50 55

pattern is being formed. Next, consider the problem of generating a 6B from the 4B. In this case the rate of the shifting movement should be twice as great as it was in the former case, since the 5 toe spring difficulty found in ordinary grading is substantially proportional to the accretion produced by the magnification. In accordance with the invention of my application above mentioned, this shifting movement is governed by 10 the length grading movement in the machine. This length grading movement is twice as great in the case of a 6B as in the case of a 5B, and therefore the shifting movement mechanism need not be changed in adjustment. A proper adjustment, once found, can be maintained unchanged throughout the production of an entire line of B patterns.

My prior invention also provided an improved 20 length grading mechanism. The manner of center grading may be taken as an illustration of the class of problems which may be dealt with by this means.

Many women's oxford shoes have uppers from 25 the vamp and instep portions of which small pieces have been cut to form an ornamental pattern. Such patterns are cut in the leather upper by means of a die similar to a clicking machine die. It is impracticable to provide a different die for each size and width because of the expense 30 involved and it is necessary to cut this ornamental pattern on the entire line of uppers with only a few dies. It is inadvisable therefore, in many cases, to grade that part of the upper which covers the upper part of the foot in the same 35 way as its rear and lower portions, because the died-out pattern will not fit the lines of the upper properly, the die being made to fit the lines of a different size. This difficulty has given rise to the practice of center grading. Suppose, for 40 example, that an entire half pattern is to be graded by this method. The cutting will begin at the upper end of the heel, and will proceed down the heel and around the bottom, the grading mechanisms being used in the ordinary way. 45 In coming back to the starting point along the top edge the length grader will be set on center while the area covered by the died-out portion is being passed (whence the name given to the practice), copying this portion of the upper edge 50 of the model without length grading it. This makes it fit the die which is actually to be used in cutting out the ornamentation. When the model wheel has reached the starting point on the model the cutter will not have reached the 55 corresponding point on the work since the bottom has been length graded and part of the top has not, and the cutting has to be finished empirically.

In order to deal with this and similar difficulties, my former invention provided an improved 60 grading mechanism, shown as a length grading mechanism, in which the length grading factor can be substantially changed without injury to the work as the work proceeds, in order, for example, to make up the loss in length grade suffered in passing a died-out portion of a pattern.

It is a principal object of the present invention to improve still further upon the invention of my prior application, Serial No. 432,866, while sacrificing none of the advantages of it and of the prior inventions mentioned.

To this end, while retaining the feature of driving the shifting mechanism by the length grading movement, I have provided an alternative means for driving the shifting mechanism 70 which is independent of the length grading move-

ment. The shifting mechanism (working in width) can thus be used when the machine is not magnifying in length. The present invention thus combines the advantage of my prior invention of application Serial No. 432,866, of driving the shifting mechanism by the grading movement, with the advantages of the prior invention of the Burke patent above mentioned, of effecting the shifting movement independently of the grading movement.

Another important feature of the invention consists in making the movement of the principal driving member of the shifting mechanism, in both ways of driving it, independent of the movements of all elements of the machine except those which are intended to drive it. In the illustrated machine the principal driving member is a swinging arc (in effect a bell-crank lever) connected to one of the principal instrumentalities, herein shown as the cutter. In accordance with this feature of the invention the arc and the cutter are relatively motionless at all times except when the arc is being driven, no matter what else may be happening in the machine. Thus, the arc can always be started from the same standard position, and its performance accurately predicted. The action of the arc is utilized to move the main fulcrum of the width grading lever, and is thus entirely unaffected by the swinging movement of the width grading lever itself in exercising its grading function.

The machine illustrated herein also provides a shifting mechanism operating to effect longitudinal displacement of longitudinally extending differential elements by virtue of a movement of a primary instrumentality widthwise of the model or work piece. This feature of the invention preserves the advantage of the invention of the Packard Patent No. 1,520,075 and at the same time provides a simpler construction than that 40 of the patent.

The present invention also provides improved grading mechanisms, for both length and width, in which the grading factors can be changed as the work proceeds, without injury to the work. 45 The mechanism herein shown is simpler and cheaper to build than that shown in my prior application and furthermore is provided for both grading mechanisms instead of merely for the length grader as therein shown.

These and other features of the invention comprising certain combinations and arrangements of parts will be apparent from the following description of a preferred embodiment of the invention shown in the drawings, in which

Fig. 9 is a detail of the width grading lever;

Fig. 10 is a diagrammatic sketch, in plan, of the machine, in which parts which lie one above the other have been horizontally displaced for the 70 sake of clearness; and

Fig. 11 is a detail view of part of the mechanism shown in Fig. 1.

The machine shown is a commercial Reed pattern grading machine, certain parts of which have 75

been removed and replaced by constructions relating to the present invention.

The main frame 10 is equipped with tracks 12 running widthwise of the machine, or toward and from the operator. This direction is called "north and south" in the pattern grading shop, and the perpendicular direction is called "east and west". In other words, the machine is looked at as if it were a map in front of an operator facing to the north. These terms will be used herein, in these significations.

A large carriage 14 is arranged to move north and south on the tracks 12. The carriage 14 has tracks 16 running east and west on which move 15 two carriages 18, 20, the former carrying the model guide or follower 22 above the model holder 24 on the frame 10, and the latter provided with north and south extending tracks 26, on which runs the cutter carriage 28 with its cutter 30. 20 The carriages 18, 20 are connected by a length grading lever 32 and its link 34, and the carriages 20 and 28 are connected by a width grading lever 36 and its link 38.

The length grading lever 32 is pivoted at its 25 end 40 to a slide 41 running north and south on the carriage 14. Near its other end it is pivoted at 42 to the carriage 18, and a so-called basket 44 is adjustable along the well-known slot in the end of the lever so that it may take positions 30 either side of the pivot 42. The link 34 is pivoted to the basket and at its other end is connected to the carriage 20. Thus, as is well known, east and west movement of the model guide 22 will cause a differential or length grading movement 35 of the carriages 18, 20, depending on the adjustment of the basket 44.

The width grading lever 36 has its eastern end pivoted to a slide 37 (Fig. 9) which runs east and west on the under side of an overhanging bar 46. 40 This structure is well known. The bar 46 has been almost entirely cut away since it lies above other parts of the machine. The pivot 47 at the western end of the grading lever 36 is carried by the carriage 20 and its basket 48 with the end of its link 38 are adjustable along a slot in the lever, as described in the case of the length grading lever 32. As is well understood, a north and south movement of the model guide 22 will move the carriages 14, 18, 20 by the same amount, will swing 45 the lever 36, whose eastern end is fixed against north and south movement, and thus cause a differential or width grading movement of the carriages 20, 28.

All the structure and operation so far described are old and well understood. The above-described action of the grading levers is herein-after called regular grading.

The illustrated machine provides mechanism for effecting a north and south movement (by 60 which expression is meant a movement in either a north or south direction) of the cutter 30 (in addition to any grading movement it may have), due purely to an east and west movement of the model guide 22. This is the shifting movement 65 above described. In my application referred to this is effected by changing the effective length of the link 38. In the machine herein shown it is effected by shifting the pivot 47 of the width grading lever 36 in a north and south direction. 70 The structure for accomplishing this is as follows (see principally Figs. 2 and 3):

A large bracket 50 is mounted on the carriage 20 by means of screws 52 (Figs. 3 and 6) seated in the holes in which the pivots of the west end 75 of the link 34 and of the width grading lever 36

are seated in the unimproved Reed machine. A screw 52 and the pivot 47 are shown slightly offset in Fig. 1. The elements 20 and 50, once relatively adjusted by the set screws 53, remain rigidly connected. This structure has been adopted for considerations of economy, it being desirable to use the structure of the old commercial machine as far as possible. The bracket 50 carries a north and south moving slide 54 on which is mounted a second and shorter north and south 10 slideable adjustable member 56. The slide 54 carries the pivot 47 of the width grading lever 36.

The member or slide 56 has a vertical shaft 58 in it with a pinion 60 on its lower end below the member 56. A handle 62 is pivoted on the upper end of the shaft 58, and when turned slightly from horizontal position can be used to turn the shaft and pinion. When the handle 62 is turned to a horizontal position, a cam on its lower face wedges against a hub 62½ on the top of the slide 56 and clamps the pinion 60 immovably to the slide. The pinion 60 engages in a rack 63 fastened to the slide 54 and thus serves as a means of adjusting the slide 56 north and south on the slide 54. The extent of such adjustment is indicated by a pointer 64 pivoted at 66 on the slide 54 and having a pin-and-slot connection at 68 with the slide 56. The pointer reads along a circular scale 70 on the slide 54. Both slides 54, 56 are held rigidly connected when the handle 62 is 20 in clamping position and are moved by a link 72 having one end pivoted on the hub 62½ and its other end pivoted on a pin 74 which by means of a nut 76 can be clamped anywhere in a slot in an arc 78 the radius of which equals the length 30 of the link 72. The pin 74 is shown in neutral position in Fig. 2 and in an operative position in Figs. 1 and 10. The arc 78 swings about the axis of a pivot pin 80 to which it is keyed. The pin 80 is mounted in a bearing in the bracket 50 40 and has a square end below the bracket fitting into a square hole in an arm 82. Below the square end the pin 80 has a stub on which is freely rotatable a pinion 84.

A little shaft 86 is mounted to move freely in a circular slot 87 in the bracket 50. It passes rotatably through a bearing in the arm 82 and then through a distance washer and then through a little pinion 88 to which it is pinned and which engages the pinion 84. It is shouldered for a clamp 45 washer 101. Its lower end is right-hand threaded into a flanged nut 90 which, when the shaft 86 is screwed up in it by the handle 92, grips a slotted link 94 fixedly between the nut 90 and the washer 101 which overlies the link a little, thus locking the link 94 to the shaft 86 and pivoting the link 94 to the arm 82. The slot in the link engages flat sides on the nut which is thus held against rotation. When the handle 92 is turned so as to unscrew the nut 90 the pinion 88 will cause the pinion 84 to turn a pinion 96 pinned on a left-hand threaded stub 98 pivoted in the north end of the arm 82 and will in the same way clamp a slotted bar 100 to the stub 98, thus pivoting the bar 100 to the arm 82. One or the other of the bars 94, 100 can thus drive the arm 82, shaft 80 and arc 78. When the handle 92 is in its central position, a cam on its lower surface can be set by pushing the handle down to clamp the bar 82 and pinion 88 to the bracket 50 by means of the collar 101 and thus prevent any movement of the arc 78. Adjustable stops 101½ are provided on the arc 78 to limit the adjustment of the pin 74.

One of the bars 94, 100, alone, will enable the machine to perform its functions, but it is convenient to have two, driving the arm 82 in opposite directions. This will sometimes avoid setting the pin 74 to the opposite side of its neutral position.

The bars 94, 100 are pivoted to a crosshead 102 having a slide arm 104 running east and west in a slideway in an arm or bracket 106 bolted on the carriage 18 (see Figs. 5 and 8). The slide arm 104 is fastened to the arm 106 by a screw 108 having a right-hand thread 110 at its end engaging a nut slidable in a T slot in the arm 106, and a left-hand thread 112 engaging the slide 104. When the screw 108 is turned right-handed it will thus clamp the elements 104, 106 together. When the screw is turned left-handed it will release the elements 104, 106 and clamp the slide 104 to a member 114 which is slidable in a guide in the top of the slide 104, the member 114 being slotted to receive the screw 108. The function of the member 114 will appear later.

An arm 116 (Fig. 2) mounted in the slide 54 carries a rack bar 118 (Fig. 4) arranged to mesh with a pinion 120 mounted on the bracket 50. This pinion carries a pointer 121 reading on a scale 122 and thus indicates the movement of the slide 54.

A latch 123 (Fig. 3) is pivoted on the arm 82 and engages a notch in the bracket 50 to lock the arm 82 in central position when desired, to prevent accidental movement of the arm.

The mechanism so far described is effective to shift the cutter 30 north and south by virtue of an east and west movement of the model guide 22. Such a movement moves the carriages 18, 20 and moves them differentially in an east and west direction owing to the action of the length grading lever 32. If then one of the bars 94, 100, which move with the carriage 18, is clamped to the bar 82 the arc 78 will be swung by an amount substantially proportional to the differential movement. This will actuate the link 72, if adjusted off the center 80, to shift the width grading lever pivot 47 north and south.

It should be noticed that the arc 78 is motionless relatively to the bracket 50 at all times except when it is being driven by one of the bars 94, 100. Thus, when it is thrown into operation by clamping one of the bars 94, 100 to it, its effect in moving the center 47 is unaffected by the position of the width grading lever 36. The model guide 22 may have been moved much or little from its initial position at the time the drive of the arc 78 is started: the arc can always be started from neutral position so that its effect in moving the center 47 is dependent only on the adjustment of the link 72 and on the differential movement of the carriages 18 and 20. I have thus preserved the advantage of the machine of my prior invention of my application Serial No. 432,866 and have effected the improvement of making the setting of the link 72 entirely independent of width grading.

This mechanism, as described, is not effective when the machine is not length grading because then there is no differential movement of the carriages 18, 20 to drive it. The shifting effect, which is sometimes desired in such a case, may be secured by the following described mechanism.

The slide 114 is pivoted to a lever 124 by a pin-and-slot connection at 126. The lever 124 is pivoted near its middle at 128 to the bracket 106 and its north end 129 is pivotally connected to the length grading lever 32 by a link 130. The

members 104 and 114 being clamped together, as above described, the movement of the length grading lever 32 itself, even though the basket 44 is set neutral, will operate the slide 104 and the remainder of the mechanism described.

It is sometimes desirable to effect an east and west shifting movement between the primary instrumentalities of the machine due to a north and south movement between them in addition to their regular grading movement due to the north and south movement. This is the same type of operation as that already described, but entirely at right angles to it. The illustrated machine also provides a simple and convenient mechanism for this purpose.

A slide bar 132 is mounted in guides 134 on one of the carriages 20, 28 so that it can slide north and south. It has pivoted to its two links 136, 138, the former of which is pivoted at 139 to the west end of the width grading lever 36. The link 138 is pivoted to a crank arm 140 which can be clamped by a screw 142 to the vertical spindle of a slotted arc 144, the spindle being pivotally mounted in the bracket 50. A link 146 has one of its pivoted ends 147 adjustable along the slot in the arc 144 and its other end pivoted on a small slide 148 which can run east and west in a slideway in the bracket 50. The movement of this slide is shown by a pointer and scale 149. The length grading link 34 is also pivoted to the slide 148 instead of directly to the bracket 50 (or carriage 20), and the slide 148 can be locked to the bracket by a screw 150 when desired. The screw 150 being loose and the pivot 147 being properly adjusted on the arc 144, a north and south movement of the model guide 22 will swing the width grading lever 36, move the links 136, 138, swing the arm 140 which will have already been clamped to the arc 144, and effect a relative east and west movement between the carriages 18, 20. When such action is not desired, the screw 142 will be loosened and the screw 150 tightened, which will lock the slide 148 to the bracket 50.

The illustrated machine also provides mechanism for varying the actual grading movements of the primary instrumentalities: that is, an east and west movement between two of the primary instrumentalities can be made to produce an east and west movement between two of them, in addition to any normal length grading movement; and a north and south movement to produce a north and south movement, in addition to the regular width grading movement. In one way of looking at the matter, such mechanism permits a change in the grading rate at some desired point in the work without causing any discontinuity in its outline. One form of mechanism for effecting this result in length grading is described and claimed in my application Serial No. 432,866, referred to. Another form is shown herein, as follows:

A slotted arc 152 is pivoted on the bracket 106 and a link 154, having one pivoted end adjustable along the slot, has its other end pivoted at 155 to the bracket 50 near the slide 148. A link 156 is pivoted at one end to the south end of the arc 152 and has a pin-and-slot clamp-pivoted connection 158 with the south end of the length grading lever 32. An east and west movement of the model guide 22 will thus rock the arc 152 by virtue of the movement of the lever 32 and the link 154 will then cause a differential movement of the carriages 18, 20.

In this case the arc 152 acts as a length grading lever itself, the function of the lever 32 being merely to drive it. The screw 150 will normally be loose when the arc 152 is in use, so that the link 34 is ineffective. Thus, the length grading factor can be changed at any time without relatively moving any of the four primary instrumentalities and therefore without causing any discontinuity or jog in the periphery of the work.

The mechanism for, in effect, altering the width grading factor is as follows: An arm 160 has a hub 162 (Fig. 3) mounted firmly on the hub of the arc 78 and swings with the arc. The arm 160 has an adjustable pivotal pin-and-slot connection at 164 with a link 166 pivoted at 168 to the west end of the width grading lever 36. If now the handle 92 is in its central position but tipped up so that the clamping cam on its lower surface is inactive, and if the latch 123 is opened, the arc 78 will be free to turn in any way, and the width grading swing of the lever 36 will turn it if the connection 164 has been made. The arc 78 will then move the center 47 as above described. In this case the arm 160 acts as a width grading lever, the action of which is algebraically additional to that of the main width grading lever 36. Obviously it can be set in operation at any time by making the above-described settings without any disturbance of the four primary instrumentalities. It is driven by the width grading lever 36, as in the case of the corresponding length grading mechanism previously described, but the lever 36 here also acts independently as a grader.

It should be noticed that all the arcs 78, 144, 152, when not in actual operation, are unaffected by the regular grading movements of the machine. Thus they can always be started into operation from neutral position and, while in that position, adjustments of the links coacting with them can be made without any other disturbance of the mechanism since in all cases the radii of the arcs are made equal to the effective lengths of their co-operating links. Since they always start into operation from neutral position their action is independent of any movements that have occurred prior to their starting into action, and can be easily predicted with accuracy.

The characteristics just described render it very easy to set the machine. It is not necessary that the arcs 78, 144 and 152 be graduated at all. Suppose, for example, that it is desired to set the machine to shift the cutter north one-quarter inch when the model guide moves west two inches, grading two sizes up. The length grader will be set two sizes up and the link 72 will be set at the center of the arc 78 and one of the bars 94, 100 will be connected to the segment. The model wheel will then be run west the two inches, thus rotating the arc 78 but causing no movement of the link 72. The link 72 will then be adjusted along the arc 78, in the direction to cause north movement of the cutter, which will now cause the center 47 to move, as shown by the pointer 121, and when this pointer reads the desired amount the machine is properly set.

The link 146 can be set on the arc 144 in the same way by means of the scale and pointer at 149. The link 154 can be set on the arc 152 by the pointer at 149. This pointer will read the absolute length grade or the variation from the grade established by the lever 32 according as the link 34 is set neutral or not while the link 154 is being set.

To sum up, there are five principal mechanisms in the disclosed machine:

A. The arc 78 which, through the elements 72, 58, 54, shifts the fulcrum 47 of the width grading lever 36; as operated by the links 94, 100 and the carriage 18; that is by the length grading movement. This mechanism effects a north and south movement between the tool 30 and the model follower 22 due to an east and west movement between the primary instrumentalities.

B. The arc 78 as driven by the length grading lever 32 through the lever 124. This mechanism has the same function as that of A above but operates when there is no length grading going on.

C. The arc 78 as driven by the width grading lever 36, through the arm 160. This mechanism alters the width grading factor by effecting a north and south movement between the tool and model follower due to a north and south movement between the primary instrumentalities.

D. The arc 152 driven by the length grading lever. This mechanism alters the length grading factor by effecting an east and west relative movement between the model follower 22 and the cutter 30 due to an east and west movement between the primary instrumentalities.

E. The arc 144 driven by the width grading lever. This mechanism effects an east and west movement between the model follower 22 and the cutter 30 due to a north and south movement between the primary instrumentalities.

In one aspect of the invention, the mechanisms D and E may be regarded as a combined mechanism for effecting an east and west movement between the cutter and model follower, operable by either grading lever, at will. In the same way the arc 78 can be regarded as characterizing a mechanism for effecting a north and south movement between the tool and the model follower, which is operable by either grading lever, at will. Having described my invention, what I claim as new and desire to secure by Letters Patent of the United States is:

1. In a pattern copying machine, four primary instrumentalities, namely, a model holder, a work holder, a model follower and a tool, grading mechanism interconnecting them to effect differential movements between a plurality of them comprising a grading lever, two distinct mechanisms for effecting relative movements between the primary instrumentalities independent of regular grading movement, and connections whereby either mechanism, at will, may be driven by the grading lever.

2. In a pattern copying machine, four primary instrumentalities, namely, a model holder, a work holder, a model follower and a tool, grading mechanism interconnecting them to effect differential movements between a plurality of them comprising two grading levers operating in substantially perpendicular directions, and mechanism for effecting relative movements between the primary instrumentalities independent of regular grading movements, said mechanism being driven by either grading lever at will.

3. In a pattern copying machine, four primary instrumentalities, namely, a model holder, a work holder, a model follower and a tool, grading mechanism interconnecting them to effect differential movements between a plurality of them comprising two grading levers operating in substantially perpendicular directions, mechanism for effecting relative movements between the primary instrumentalities in one of these two directions independent of regular grading movement, said mechanism being driven by either grading lever,

at will, and mechanisms each comprising common elements of the grading mechanism, but including different grading levers, and arranged to be driven by the grading levers respectively, for 5 effecting relative movements between the primary instrumentalities in the other of the two said directions.

4. In a pattern copying machine, four primary instrumentalities, namely, a model holder, a work 10 holder, a model follower and a tool, mechanism interconnecting them to cause them to move relatively to reproduce a model in a work piece, comprising a grading lever connected to two of them for producing differential movements of the 15 two, and a second lever operatively located between the grading lever and one of said two primary instrumentalities and swung by the movement of the grading lever, said second lever being also arranged to move said last-named instrumentality independently of any regular grading movement in the machine.

5. In a pattern copying machine, four primary instrumentalities, namely, a model holder, a work 20 holder, a model follower and a tool mechanism interconnecting them to cause them to move relatively to reproduce a model in a work piece, comprising a grading lever connected to two of them for producing differential movements of the two, and a second lever operatively located between 25 the grading lever and one of said two primary instrumentalities and swung by the movement of the grading lever, said second lever being also arranged to cause relative movement between some of the primary instrumentalities independently 30 of any regular grading movement in the machine.

6. In a pattern copying machine, four primary instrumentalities, namely, a model holder, a work 35 holder, a model follower and a tool, mechanism interconnecting them to cause them to move relatively to reproduce a model in a work piece, comprising two sliding carriages arranged for differential movement in one direction and for identical movement in a direction transverse thereto, a 40 third carriage mounted on one of the said two carriages to slide thereon in the said transverse direction, a grading lever fulcrumed on one of the two first-mentioned carriages and connected to another of the three carriages, and a second lever 45 fulcrumed on one of the two first-mentioned carriages and connected to the grading lever and having a connection with one of the other two carriages, whereby the movement of the grading lever may cause a relative movement between the 50 carriage on which the second lever is fulcrumed and the carriage with which it has the said connection.

7. In a pattern copying machine, four primary instrumentalities, namely, a model holder, a work 55 holder, a model follower and a tool, mechanism interconnecting them to cause them to move relatively to reproduce a model in a work piece, comprising a grading lever connected to two of them for producing differential movement of the two, and a second lever adjustably connected between 60 the grading lever and one of said two primary instrumentalities and swung by the movement of the grading lever and arranged to move said last-named instrumentality independently of any 65 regular grading movement in the machine, the movement produced by said last-named lever being in a direction transverse to that of the movement produced by said grading lever.

8. In a pattern copying machine, four primary 70 instrumentalities, namely, a model holder, a

work holder, a model follower and a tool, mechanism interconnecting them to cause them to move relatively to reproduce a model in a work piece, comprising a grading lever connected between two of them for producing differential movements of the two, and a second lever connected between the grading lever and one of the said two primary instrumentalities and swung by the movement of the grading lever and arranged to move said last-named instrumentality independently of any movement thereof due to the grading action of said grading lever. 10

9. In a pattern copying machine, four primary instrumentalities, namely, a model holder, a work 15 holder, a model follower and a tool, mechanism interconnecting them to cause them to move relatively to reproduce a model in a work piece, comprising two sliding carriages arranged for differential movement in one direction and for identical movement in a direction transverse 20 thereto, a third carriage mounted in one of the said two carriages to slide thereon in the said transverse direction, a slide mounted on one of the two first-named carriages arranged to move parallel to the direction of movement of the third 25 carriage, a grading lever fulcrumed on the slide and connected to the third carriage, a second grading lever fulcrumed on the other of the two carriages, a rocking lever mounted on the former of the two carriages and connected to the slide, 30 a second slide mounted on the other of the two carriages, a connection between the second slide and the rocking lever, and means for connecting the second slide to the carriage on which it is mounted or to the second grading lever, at will. 35

10. In a pattern copying machine, four primary instrumentalities, namely, a model holder, a work holder, a model follower and a tool, mechanism interconnecting them to cause them to move relatively to reproduce a model in a work 40 piece, comprising two sliding carriages arranged for differential movement in one direction and for identical movement in a direction transverse thereto, a third carriage mounted in one of the said two carriages to slide thereon in the said 45 transverse direction, a grading lever fulcrumed on one of the two carriages and connected to the other, a second lever fulcrumed on the other of the two carriages and connected to the third carriage, and a driving mechanism for the second 50 lever connectible at will to the grading lever or to the carriage on which the grading lever is mounted.

11. In a pattern copying machine, four primary instrumentalities, namely, a model holder, a 55 work holder, a model follower and a tool, mechanism interconnecting them to cause them to move relatively to reproduce a model in a work piece, comprising two sliding carriages arranged for differential movement in one direction and for 60 identical movement in a direction transverse thereto, a third carriage mounted in one of the said two carriages to slide thereon in the said transverse direction, a grading lever fulcrumed on one of the two carriages and connected to the 65 other, a second lever fulcrumed on the other of the two carriages and connected to the third carriage, and a connection between the second lever and that carriage on which the grading lever is mounted, the grading lever forming a part of said 70 connection or not, at the will of the operator.

12. In a pattern copying machine, four primary instrumentalities, namely, a model holder, a work holder, a model follower and a tool, mechanism interconnecting them to cause them to 75

move relatively to reproduce a model in a work piece, comprising a grading lever connected to two of them for producing differential movement of the two, and a second lever connected to the 5 grading lever and having its fulcrum movable relatively to that of the grading lever and arranged, when swung on its fulcrum, to move the fulcrum of the grading lever to effect a movement of a primary instrumentality independently 10 of the regular grading movement simultaneously going on in the machine.

13. In a pattern copying machine, four primary instrumentalities, namely, a model holder, a work holder, a model follower and a tool, mechanism 15 interconnecting them to cause them to move relatively to reproduce a model in a work piece, comprising a swinging member connected to one of the said primary instrumentalities and arranged to be normally unrotated, and 20 a second connection between the swinging member and another of the said primary instrumentalities arranged to be rendered operable at the will of the operator whereby a relative movement in one direction between the two said primary 25 instrumentalities, which are connected to the swinging member, will turn the swinging member to effect relative movement between the two said primary instrumentalities in a transverse direction.

30 14. In a pattern copying machine, four primary instrumentalities, namely, a model holder, a work holder, a model follower and a tool, mechanism interconnecting them to cause them to move relatively to reproduce a model in a work piece, comprising a grading lever connected to two of them 35 for producing differential movement of the two, and a second lever adjustably connected to the grading lever and swung by the movement thereof, said last-named lever being also connected to a 40 said primary instrumentality and arrangement to move said last-named instrumentality independently of any regular grading movement in the machine, said movement produced by said last-named lever being in a direction parallel to 45 that produced by the grading lever.

15. In a pattern copying machine, four primary instrumentalities, namely, a model holder, a work holder, a model follower and a tool, grading mechanism interconnecting them to effect differential movements between a plurality of them 50 comprising two grading levers operating in substantially perpendicular directions, and mechanism for imparting to a said primary instrumentality a movement in addition to any normal grading movement, said mechanism being driven by either grading lever at will.

16. In a pattern copying machine, four primary instrumentalities, namely, a model holder, a work holder, a model follower and a tool, mechanism 60 interconnecting them to cause them to move relatively to reproduce a model in a work piece, comprising a grading lever connected to two of them for producing differential movement of the two, and a second lever operatively located between 65 the grading lever and one of said two primary instrumentalities and swung by the movement of the grading lever, said last-named lever being also adjustably connected to a said primary instrumentality and arranged to move said last-named instrumentality independently of any movement thereof due to the grading action of said grading lever.

17. In a pattern copying machine, four primary instrumentalities, namely, a model holder, a work holder, a model follower and a tool, mechanism 75

interconnecting them to cause them to move relatively to reproduce a model in a work piece, comprising two sliding carriages arranged for differential movement in one direction and for identical movement in a direction transverse thereto, a third carriage mounted on one of the said two carriages to slide thereon in the said transverse direction, a grading lever fulcrumed on one of the first-mentioned two carriages and connected to the other, and a second lever fulcrumed on one of the two first-mentioned carriages and connected to the other and to the grading lever, whereby the movement of the grading lever operates the second lever to effect a relative movement between two of the three carriages mentioned.

18. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted on one of the said two carriages to slide thereon in the said transverse direction, a grading lever on one of the two first-mentioned carriages and connected to the other, and a second lever fulcrumed on one of the two first-mentioned carriages and having a driving connection with the third carriage, and means for driving the second lever by the movement of the grading lever, whereby the movement of the grading lever may effect relative movement between the third carriage and one of the other two carriages.

19. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted on one of the said two carriages to slide thereon in the said transverse direction, a grading lever fulcrumed on one of the two first-mentioned carriages and connected to the other, and a second lever fulcrumed on one of the two first-mentioned carriages and connected to the grading lever and having a connection with one of the other two carriages, whereby the movement of the grading lever may cause a relative movement between the carriage on which the second lever is fulcrumed and the carriage with which it has the said connection.

20. In a pattern copying machine, four primary instrumentalities, namely, a model holder, a work holder, a model follower and a tool, mechanism interconnecting them to cause them to move relatively to reproduce a model in a work piece, comprising a grading lever mounted on one of them and connected to another of them for producing differential movement of the two, and a second lever connected to the grading lever and having its fulcrum mounted on the primary instrumentality on which the grading lever is mounted and swung by the movement of the grading lever, said last-named lever having a connection with a said primary instrumentality and being arranged to move said last-named instrumentality independently of any regular grading movement in the machine.

21. In a pattern copying machine, four primary instrumentalities, namely, a model holder, a work holder, a model follower and a tool, mechanism

- interconnecting them to cause them to move relatively to reproduce a model in a work piece, comprising a grading lever connected to two of them for producing differential movement of the two, and a second lever operatively located between the grading lever and one of the said two primary instrumentalities and swung by the movement of the grading lever and arranged to cause relative movement between some of the primary instrumentalities independently of any regular grading movement in the machine, said independent movement being substantially perpendicular to the direction of grading differential movement accomplished by said lever.
22. In a pattern copying machine, four primary instrumentalities, namely, a model holder, a work holder, a model follower and a tool, mechanism interconnecting them to cause them to move relatively to reproduce a model in a work piece, comprising a grading lever connected to two of them for producing differential movement of the two, and a second lever operatively located between the grading lever and one of said two primary instrumentalities and swung by the movement of the grading lever and arranged to move one of said two primary instrumentalities independently of any movement thereof due to the grading action of said grading lever, said independent movement being substantially perpendicular to the direction of grading differential movement accomplished by said lever.
23. In a pattern copying machine, four primary instrumentalities, namely, a model holder, a work holder, a model follower and a tool, mechanism interconnecting them to cause them to move relatively to reproduce a model in a work piece, comprising a grading lever connected to two of them for producing differential movements of the two, and a second lever connected to the grading lever and swung by the movement thereof, said last-named lever being also connected to a said primary instrumentality and arranged to move said last-named instrumentality independently of any regular grading movement in the machine, said independent movement being substantially in the direction of grading differential movement accomplished by said lever.
24. In a pattern copying machine, four primary instrumentalities, namely, a model holder, a work holder, a model follower and a tool, mechanism interconnecting them to cause them to move relatively to reproduce a model in a work piece, comprising a grading lever connected to two of them for producing differential movements of the two, and a second lever connected to the grading lever and swung by the movement thereof, said last-named lever being also connected to a said primary instrumentality and arranged to cause relative movement between some of the primary instrumentalities independently of any regular grading movement in the machine, said independent movement being substantially in the direction of grading differential movement accomplished by said lever.
25. In a pattern copying machine, four primary instrumentalities, namely, a model holder, a work holder, a model follower and a tool, mechanism interconnecting them to cause them to move relatively to reproduce a model in a work piece, comprising a grading lever connected to two of them for producing differential movement of the two, and a second lever connected to the grading lever, having its fulcrum movable relatively to that of the grading lever, and swung by the movement of the grading lever, said last-named lever being connected to a said primary instrumentality and arranged to move said last-named instrumentality independently of any regular grading movement in the machine.
26. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted on one of the said two carriages to slide thereon in the said transverse direction, a grading lever fulcrumed on one of the two first-mentioned carriages and connected to another of the three carriages mentioned, and a second lever fulcrumed on the same carriage as the grading lever and connected to the grading lever and to the other of the two first-mentioned carriages whereby swinging of the grading lever may effect relative movement between the two first-mentioned carriages.
27. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted in one of the said two carriages to slide thereon in the said transverse direction, a slide mounted on one of the two first-mentioned carriages arranged to move parallel to the direction of movement of the third carriage, a grading lever fulcrumed on the slide and connected to the third carriage, a rocking lever mounted on one of the two carriages and connected to the slide, a second slide mounted on the other of the two carriages, a connection between the second slide and the rocking lever, and means for connecting the second slide to the carriage on which it is mounted.
28. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted in one of the said two carriages to slide thereon in the said transverse direction, a slide mounted on one of the two first-mentioned carriages arranged to move parallel to the direction of movement of the third carriage, a grading lever fulcrumed on the slide and connected to the third carriage, and a second lever pivoted on that carriage on which the slide is mounted, connected to the slide and connected also to that one of the first-named two carriages on which the slide is not mounted.
29. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted in one of the said two carriages to slide thereon in the said transverse direction, a slide mounted on one of

the two first-named carriages arranged to move parallel to the direction of movement of the third carriage, a grading lever fulcrumed on the slide and connected to the third carriage, and a lever 5 formed of two crossed arms pivoted on one of the carriages, and having one pair of arms connected to the slide and the other pair of arms connected to that one of the first two carriages on which the slide is not mounted.

10 30. In a pattern copying machine, four primary instrumentalities, namely, a model holder, a work holder, a model follower and a tool, mechanism interconnecting them to cause them to move relatively to reproduce a model in a work 15 piece, comprising two sliding carriages arranged for differential movement in one direction and for identical movement in a direction transverse thereto, a third carriage mounted in one of the said two carriages to slide thereon in the said 20 transverse direction, a slide mounted on one of the two first-named carriages arranged to move parallel to the direction of movement of the third carriage, a grading lever fulcrumed on the slide and connected to the third carriage, and a second 25 lever pivoted on one of the carriages, connected to the slide and connected also to that one of the first-named two carriages on which the slide is not mounted.

31. In a pattern copying machine, four primary 30 instrumentalities, namely, a model holder, a work holder, a model follower and a tool, mechanism interconnecting them to cause them to move relatively to reproduce a model in a work piece, comprising two sliding carriages arranged for 35 differential movement in one direction and for identical movement in a direction transverse thereto, a third carriage mounted on one of the said two carriages to slide thereon in the said transverse direction, a lever fulcrumed on one of the two first-mentioned carriages, means for 40 connecting the lever to the other of the two first-mentioned carriages at points on opposite sides of its fulcrum, and a connecting mechanism between the lever and the third carriage, whereby 45 relative movement of the two first-named carriages will effect relative movement between the carriage on which the lever is fulcrumed and the third carriage.

32. In a pattern copying machine, four primary 50 instrumentalities, namely, a model holder, a work holder, a model follower and a tool, mechanism interconnecting them to cause them to move relatively to reproduce a model in a work piece, comprising a grading member arranged to 55 move two of them differentially, and a swinging member arranged to be swung by the differential movement and connected to a third of the primary instrumentalities to move it in a direction transverse to the said differential movement, 60 said swinging movement of the swinging member being dependent solely upon said differential movement.

33. In a pattern copying machine, four primary 65 instrumentalities, namely, a model holder, a work holder, a model follower and a tool, mechanism interconnecting them to cause them to move relatively to reproduce a model in a work piece, comprising a grading lever connected to 70 two of them for producing differential movement of the two, a slide on which a fulcrum of the grading lever is mounted, said slide being inoperative in regular grading, and means for operating the slide when desired, comprising a connection between two of the said primary instrumentalities, the connection being operated by 75

relative grading movement of the two primary instrumentalities.

34. In a pattern copying machine, four primary instrumentalities, namely, a model holder, a work holder, a model follower and a tool, mechanism interconnecting them to cause them to move relatively to reproduce a model in a work piece comprising two sliding carriages arranged for differential movement in one direction and for identical movement in a direction transverse 10 thereto, a third carriage mounted on one of the said two carriages to slide thereon in the said transverse direction and having a connection therewith, said connection comprising a first lever, a grading lever fulcrumed on one of the two first-mentioned carriages and connected to the other of said two first-mentioned carriages, and a third lever fulcrumed on one of the two carriages and connected to the first lever and to the grading lever, whereby the movement of the grading lever operates the third lever to effect a relative movement between one of the two first-mentioned carriages and the third carriage. 15

35. In a pattern copying machine, four primary instrumentalities, namely, a model holder, a work holder, a model follower and a tool, mechanism interconnecting them to cause them to move relatively to reproduce a model in a work piece, comprising grading levers connected to two of them for producing differential movements of 30 the two, a slide on which a fulcrum of one grading lever is mounted, said slide being inoperative in regular grading, and means for operating the slide when desired, comprising a connection between the slide and the other grading lever. 35

36. In a pattern copying machine, four primary instrumentalities, namely, a model holder, a work holder, a model follower and a tool, mechanism interconnecting them to cause them to move relatively to reproduce a model in a work 40 piece, comprising a grading lever connected to two of them for producing differential movement of the two, and a second lever connected to the grading lever, having its fulcrum fixed in position relatively to that of the said grading lever, 45 and swung by the movement of the grading lever, said last-named lever having a connection with a said primary instrumentality and being arranged to move said last-named instrumentality independently of any movement thereof due 50 to the grading action of said grading lever.

37. In a pattern copying machine, four primary instrumentalities, namely, a model holder, a work holder, a model follower and a tool mechanism interconnecting them to cause them to move 55 relatively to reproduce a model in a work piece, comprising two sliding carriages arranged for differential movement in one direction and for identical movement in a direction transverse thereto, a third carriage mounted in one of the 60 said two carriages to slide thereon in the said transverse direction, a grading lever fulcrumed on one of the two carriages and connected to the other, a second lever fulcrumed on the other of the two carriages and connected to the third carriage, and a connection between the second lever and the grading lever to swing the second lever. 65

38. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse 70

- thereto, a third carriage mounted on one of the said two carriages to slide thereon in the said transverse direction, a grading lever on one of the two first-mentioned carriages and connected to the other, a second lever fulcrumed on one of the two first-mentioned carriages and having a driving connection with the third carriage, and a link connecting the second lever with the grading lever whereby the movement of the grading lever 5 may effect relative movement between the third carriage and one of the other two carriages, said movement being in the said transverse direction.
39. In a pattern copying machine, four primary instrumentalities, namely, a model holder, a work holder, a model follower and a tool, mechanism interconnecting them to cause them to move relatively to reproduce a model in a work piece, comprising a grading lever connected to two of them for producing differential movement 10 of the two, and a second lever adjustably connected to the grading lever and swung by the movement thereof, said last-named lever being also connected to a said primary instrumentality and arranged to move said last-named instrumentality independently of any movement thereof due to the grading action of said grading lever, said independent movement being substantially in the direction of grading differential movement accomplished by said lever.
40. In a pattern copying machine, four primary instrumentalities, namely, a model holder, a work holder, a model follower and a tool, mechanism interconnecting them to cause them to move relatively to reproduce a model in a work piece, comprising a grading lever connected to two of them for producing differential movement of the two, and a second lever connected to the grading lever and having its fulcrum movable relatively to that of the said grading lever and swung by the movement thereof, said last-named lever having a connection with a said primary instrumentality and arranged to move said last-named instrumentality independently of any movement thereof due to the grading action of said grading lever, said independent movement being substantially in the direction of grading differential movement accomplished by virtue of the said relative movement between the fulcra of the grading lever 20 and the second-named lever.
41. In a pattern copying machine, four primary instrumentalities, namely, a model holder, a work holder, a model follower and a tool, mechanism interconnecting them to cause them to move relatively to reproduce a model in a work piece, comprising a grading lever carried by one of them and connected to another of them for producing differential movement of the two, a slide on that primary instrumentality which carries the grading lever and on which slide a fulcrum of the grading lever is mounted, said slide being inoperative in regular grading, and means for operating the slide when desired, comprising a connection between the slide and the grading lever.
42. In a pattern copying machine, four primary instrumentalities, namely, a model holder, a work holder, a model follower and a tool, mechanism interconnecting them to cause them to move relatively to reproduce a model in a work piece, comprising a grading lever connected to two of them for producing differential movement of the two, and a second lever connected to the grading lever, having its fulcrum movable relatively to that of the grading lever, and swung

by the movement of the grading lever, said last-named lever being connected to a said primary instrumentality and arranged to move said last-named instrumentality independently of any movement thereof due to the grading action of said grading lever.

43. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted in one of the said two carriages to slide thereon in the said transverse direction, a slide mounted on one of the two first-named carriages arranged to move parallel to the direction of movement of the third carriage, a grading lever fulcrumed on the slide 20 and connected to the third carriage, and a second lever pivoted on one of the carriages, connected to the slide and to the grading lever, whereby the movement of the grading lever moves the second lever to shift the slide and with it the grading lever fulcrum.

44. In a pattern copying machine, four primary instrumentalities, namely, a model holder, a work holder, a model follower and a tool, mechanism interconnecting them to cause them to move relatively to reproduce a model in a work piece, comprising a grading lever connected to two of them for producing differential movements of the two, and a second lever connected to the grading lever and swung by the movement thereof, said last-named lever being also connected to a said primary instrumentality and arranged to move said last-named instrumentality independently of any movement thereof due to the grading action of said grading lever, said independent movement being substantially in the direction of grading differential movement accomplished by said lever.

45. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted on one of the said two carriages to slide thereon in the said transverse direction, a grading lever on one of the two first-mentioned carriages and connected to the other, and a second lever, fulcrumed on one of the two first-mentioned carriages and having a connection with the third carriage, whereby the movement of the grading lever may effect relative movement between the third carriage and one of the other two carriages, said movement being in the said direction of differential movement.

46. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted on one of the said two carriages to slide thereon in the said transverse direction, a grading lever fulcrumed on one of the two first-mentioned carriages and

connected to the other, and a second lever fulcrumed on one of the two carriages and connected to the other and to the grading lever, whereby the movement of the grading lever operates the second lever to effect a relative movement between the two first-mentioned carriages.

47. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted on one of the said two carriages to slide thereon in the said transverse direction, a grading lever fulcrumed on one of the two first-mentioned carriages and connected to the other, and a second lever fulcrumed on the same carriage as the grading lever and connected to the grading lever and to the other of the two first-mentioned carriages whereby swinging of the grading lever may effect relative movement between the two first-mentioned carriages.

48. In a pattern copying machine, four primary instrumentalities, namely, a model holder, a work holder, a model follower and a tool, mechanism interconnecting them to cause them to move relatively to reproduce a model in a work piece, comprising a grading lever arranged for producing differential movement of two of them, and a second lever adjustably connected to the grading lever and swung by the movement thereof, said last-named lever being adjustably connected to a said primary instrumentality and arranged to move said last-named instrumentality independently of any movement thereof due to the grading action of said grading lever, said

independent movement being substantially perpendicular to the direction of grading differential movement accomplished by said lever.

49. In a pattern copying machine, four primary instrumentalities, namely, a model holder, a work holder, a model follower and a tool, mechanism interconnecting them to cause them to move relatively to reproduce a model in a work piece, comprising two sliding carriages arranged for differential movement in one direction and for identical movement in a direction transverse thereto, a third carriage mounted in one of the said two carriages to slide thereon in the said transverse direction, a grading lever connecting the third carriage and the carriage on which it is mounted, a second lever arranged to be moved by the grading lever, and a connection between the second lever and the other of the two first-mentioned carriages.

50. In a pattern copying machine, four primary instrumentalities, namely, a model holder, a work holder, a model follower and a tool, mechanism interconnecting them to cause them to move relatively to reproduce a model in a work piece, comprising a grading lever arranged for producing differential movement of two of them, and a second lever connected to the grading lever and having its fulcrum movable relatively to that of the said grading lever and swung by the movement thereof, said last-named lever having a connection with a said primary instrumentality and arranged to move said last-named instrumentality independently of any movement thereof due to the grading action of said grading lever, said independent movement being substantially perpendicular to the direction of grading differential movement accomplished by said lever.

GEORGE FRANCIS RYAN.
